UNITED STATES PATENT OFFICE.

GERHART HAMMER AND HARALD K. BERSETH, OF COLFAX, WISCONSIN.

DESIGN FOR A STATUETTE.

Application filed December 31, 1925. Serial No. 15,919. Term of patent 14 years.

To all whom it may concern:

Be it known that we, GERHART HAMMER and HARALD K. BERSETH, citizens of the United States of America, residing at Colfax, in the county of Dunn and State of Wisconsin, have invented a new, original and ornamental Design for a Statuette, of which the following is a specification, reference being had to the accompanying drawing, forming a part hereof.

In the drawing:

Fig. 2 is a similar view of the opposite side showing the design.

We claim:

The ornamental design for a statuette, as shown.
